CYLINDER AND CONCAVE MEANS FOR
SHELLING PEANUTS

Frank Funderburk, Thomasville, Ga.

Application February 20, 1946; Serial No. 648,899

3 Claims. (Cl. 146—13)

1

The invention relates to a nut shelling machine, and more especially to a peanut shelling apparatus.

The primary object of the invention is the provision of an apparatus of this character, wherein an eccentric basket has within the same, a beater, so that a shelling operation will take place with dispatch, and with a minimum of labor on the part of an operator of such machine.

Another object of the invention is the provision of an apparatus of this character, wherein the basket and beater are of novel construction and interfitted in a unique manner with resultant high speed shelling action in the use of the said apparatus.

A further object of the invention is the provision of an apparatus of this character, which is simple in construction, thoroughly reliable and efficient in operation, strong, durable, readily and easily operated, possessed of few parts, readily accessible, and inexpensive to manufacture.

With these and other objects in view the invention consists in the features of construction, combination and arrangement of parts as will be hereinafter more fully described, illustrated in the accompanying drawings, which show the preferred embodiment of the invention, and pointed out in the claims hereunto appended.

In the accompanying drawings:

Figure 1 is a side view of the apparatus constructed in accordance with the invention.

Figure 2 is a top plan view thereof.

Figure 3 is a sectional view taken approximately on the line 3—3 of Figure 1 looking in the direction of the arrows.

Figure 4 is a perspective view of the beater.

Figure 5 is a perspective view of the basket.

Similar reference characters indicate corresponding parts throughout the several views in the drawings.

Referring to the drawings in detail, the apparatus constituting the present invention comprises, a stand having side base sills 10 arranged in spaced parallel relation to each other with cross struts 11 therebetween, and fastened by fasteners 12, while rising vertically from the level of the sills 10 are upstanding supporting frames 13 carrying a feed hopper 14. This hopper 14 at the discharge throat 15 thereof has communication with a basket.

The basket, in the form of a cylinder or shell, involves eccentric shaped end heads 16 about which is disposed a perforated or slotted cylindrical sheet metal body section 17, the perforations or slots being denoted at 18. The section 17 has

2

an open entrance area confronted by edge flanges 19 and 20, respectively, the latter flange 19 contacting abutment shoulders 21 created at the eccentric swells 22 of the end heads 16 and initially engageable with these flanges 19 and 20 are hook-like tightening or stretching clamps or bolts 23 having winged nuts 24 adjustable thereon, so that such section 17 can be drawn tightly about the heads 16 and in this condition set within the throat 15, as well as permitting removal of such section 17 from the heads when desired, for replacement of a substitute section. The setting of the basket within the apparatus is best shown in Figures 1, 2 and 3 of the drawings. The open entrance area of the basket registers with the discharge throat of the hopper 14.

The basket is stationarily held in the apparatus and has eccentrically disposed therein a rotary beater or rotor having the circular disk-like ends 25 and beater bars 26, respectively. This beater is fixed to a center axle 27, having clearance through the end heads 16 of the basket and journaled in bearings 28 on the supporting frames 13 outside of the hopper 14, the axle 27 being provided with a crank handle 29 for the manual turning thereof to effect the rotation of the beater within the basket for the shelling of peanuts delivered to the latter from the hopper through the open discharge area before mentioned.

30 The hopper 14, above the open area of the throat 15, has hinged trap doors 30 and 31, respectively, which are swingable against the hopper when in open position, but when in closing position cover the open area of the throat, as best seen in Figures 1 and 2 of the drawings.

35 The shelled nuts and waste are discharged through the slots or perforations 18, in the section 17 of the basket. The beater in the working thereof shells the peanuts rapidly or with dispatch.

40 What is claimed is:

1. In a peanut shelling machine, the combination which comprises a stationary horizontally disposed perforated wall cylindrical basket having an elongated opening providing a throat in the upper surface and with the perforated wall extended from the throat at one side thereof positioned a greater distance from the center than the wall extended from the opposite side of the 45 throat, a rotor having spaced longitudinally extended beater bars on the surface positioned in said basket, a shaft extended longitudinally through the basket positioned on the center thereof and providing mounting means for the rotor whereby the rotor is positioned concentric to the 50

basket, a hand crank on the outer end of the shaft, a hopper in which the basket is positioned having side walls spaced from the basket and having converging panels in the upper ends sloping toward the throat of the basket, and doors hinged to the sloping panels of the hopper and positioned to retain the basket in operative position in the hopper.

2. In a peanut shelling machine, the combination which comprises a stationary horizontally disposed perforated wall cylindrical basket having an elongated opening providing a throat in the upper surface and with the perforated wall extended from the throat at one side thereof positioned a greater distance from the center than the wall extended from the opposite side of the throat, said perforated cylindrical wall of the basket having extended flanges on the edges thereof positioned at the sides of the throat, heads in the basket, bolts having hook shaped ends extended through the flange at one side of the throat and hooked over the flange at the opposite side for clamping the said perforated wall of the basket to the said heads, a rotor having spaced longitudinally extended beater bars on the surface positioned in said basket, a shaft extended longitudinally through the basket positioned on the center thereof and providing mounting means for the rotor whereby the rotor is positioned concentric to the basket, a hand crank on the outer end of the shaft, a hopper in which the basket is positioned having side walls spaced from the basket and having converging panels in the upper ends sloping towards the throat of the basket, and doors hinged to the sloping panels of the hopper and positioned to retain the basket in operative position in the hopper.

3. In a peanut shelling machine, the combina-

tion which comprises a stationary horizontally disposed perforated wall cylindrical basket having an elongated opening providing a throat in the upper surface and with the perforated wall extended from the throat at one side thereof positioned a greater distance from the center than the wall extended from the opposite side of the throat, a rotor having spaced longitudinally extended beater bars on the surface positioned in said basket, a shaft extended longitudinally through the basket positioned on the center thereof and providing mounting means for the rotor whereby the rotor is positioned concentric to the basket, a hand crank on the outer end of the shaft, a hopper in which the basket is positioned having side walls spaced from the basket and having converging panels in the upper ends sloping toward the throat of the basket, and doors hinged to the sloping panels of the hopper and positioned to engage the flanges of the basket to retain the basket in operative position in the hopper, said doors providing means for removing the basket and rotor from the hopper.
